UNITED STATES PATENT OFFICE

127,645

DESIGN FOR AN APRON

Ada Quinn and Mary T. Hasle, Ogden, Utah

Application August 22, 1940, Serial No. 94,569

Term of patent 3½ years

To all whom it may concern:

Be it known that we, Ada Quinn and Mary T. Hasle, citizens of the United States, residing at Ogden, in the county of Weber and State of Utah, have invented a new, original, and ornamental Design for Aprons, of which the following is a specification, reference being had to the accompanying drawing, forming part thereof.

The figure is a plan view of an apron, showing our new design.

We claim:

The ornamental design for an apron, as shown.

ADA QUINN.
MARY T. HASLE.
